CALCULATING MACHINE AND RECORDING
AND THE LIKE MACHINE

**Kurt Aurbach, Essen, Germany, assignor, by
mesne assignments, to The National Cash Reg-
ister Co., Dayton, Ohio, a corporation of Mary-
land**

Application November 23, 1933, Serial No. 699,468
In Germany December 6, 1932

27 Claims.

(Cl. 235—2)

This invention relates to bookkeeping or accounting machines and has for its principal object the detection of mistakes in copying numbers or combinations of characters and therefore improving the accuracy with which such numbers or characters are copied, for example where the operator of a bookkeeping or accounting machine reads a number from a record and sets it up on the keyboard of the machine. There are many operations where it is necessary to copy numbers, sometimes quite lengthy ones, either to transcribe said numbers from one paper to another, or to introduce the numbers into a machine to serve as part of a computation. A familiar instance of this problem is presented by the ordinary passbook now in extensive use in savings banks. Such a passbook contains a column in which appears a patron's balance following the last transaction (deposit or withdrawal); other columns for deposits and withdrawals; a column for the date of transactions; and a column for the patron's account number and other identifying data. It is now common to have a calculating machine especially arranged for such a passbook. The operator reads the old balance from the book, sets it up on the keyboard, and operates the machine to enter the old balance. After this operation he inserts the passbook in the machine, enters the deposit or withdrawal, and takes the new balance. The deposit or withdrawal and the new balance are printed in the passbook in their appropriate columns, together with the date of the transaction and the other identifying data.

It is plainly seen that if an error is made, either in reading the old balance from the passbook or in setting it up on the keyboard, the error will be carried through to the new balance and may not be detected for considerable time.

In the meantime, should the error be in favor of the patron, he may be tempted immediately to close his account, with a resulting loss to the bank.

The custom in the past has been to employ a lengthy checking system of old balance pick-ups whenever a depositor closes his account or makes a large withdrawal. This entails a loss of time and an expense which the present invention seeks to overcome by providing a means whereby the operator is informed when he has incorrectly read or set up the old balance.

Other objects of the invention are to provide a novel means of preventing the depression of certain keys except in proper sequence, so as to insure that the old balance will be picked up only

once for each transaction, and that a deposit or withdrawal will not be entered before the old balance is picked up.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

General description

In general the invention includes a mechanism that employs the differential movement of the printer racks to compute a short symbol of the numbers set on the printing wheels by these racks. This calculation embraces not only the movement of the racks setting up the amount, but those setting up the account number as well. This computed symbol is immediately conveyed by appropriate racks to the printing mechanism and is printed in the passbook together with the other data of the transaction.

Such a calculation takes place when the machine is operated to take the new balance at the end of a transaction where the patron has made a deposit or withdrawal.

Now, when the patron again presents his passbook to have a deposit or withdrawal recorded therein, the bank teller will set up the patron's old balance, account number, and symbol number from the passbook, and also depress the appropriate transaction totalizer selecting keys, and operate the machine to enter the old balance. When the differentials for the amount and account number are adjusted under control of the depressed keys, their printing racks are correspondingly adjusted, so that the symbol calculated for the new balance in the previous transaction will again be calculated as the symbol for the present old balance. This calculating also causes an adjustment of one side of a comparing mechanism to a position corresponding to the computed symbol. Depression of the proper symbol keys causes the movement of the differential mechanism for these banks to adjust the other half of the comparing mechanism to a position corresponding to the symbol keys depressed. If the proper keyboard set-up was made, the comparing mechanism will allow the transaction to be completed in the proper way. If, however, a mistake was made in setting up the amount, account number, or symbol number, the two sides of the comparing mechanism will not be correspondingly adjusted, with the result that the machine will be prevented from completing a proper recording of the transaction, so that the operator will be apprised of his mistake.

Locking mechanism is provided to prevent the entry of the old balance more than once during a transaction and also to prevent the entry of a deposit or withdrawal before the old balance is picked up.

Detailed description

The keyboard of the machine (Fig. 1) has eight rows of amount keys 10, four rows of account number keys 11, three rows of symbol keys 12, three rows of totalizer selecting keys 13, 14, and 15, with their corresponding levers 16, a lever 17 to take balances from the balance totalizer, a kind of operation lever 18, and a motor bar 19.

The mechanism in this machine illustrates the use of a symbol having as few as three decimal places to control a keyboard setting involving as many as twelve decimal places or rows. In this machine the three rows of symbol keys 12 control the setting of the account number keys 11 and the amount keys 10.

Racks 24 (Figs. 7—A, 7—B, 10—A, and 10—B), fitted in guides such as 29, are differentially shifted under control of the keys 10 and 11, by any suitable form of differential mechanism, one form suitable for the purpose being shown in United

and a slightly different form in United States Patent No. 2,039,143, of the same inventor. Since the particular type or detailed operation of the differential mechanism is not essential to an understanding of the invention, it will not be described, although it is generally shown in Fig. 6. Three racks 47 (Figs. 10—A and 10—B) lie parallel to the racks 24 and are shifted differentially under control of the symbol keys 12. The racks 24 mesh with pinions 25 (Figs. 7—A, 7—B, and 10—B) connected to printing type wheels 20 by pinions 21, 22, and 23 and the nested sleeves 26. By these connections the keyboard setting of the transaction is transmitted to the printing mechanism. The racks 47, controlled by the symbol keys, have no connection with the printing wheels, but transmit their settings to three wheels 86, 88, and 90 (Figs. 7—B, 9, and 11—B) for a purpose to be later mentioned.

The racks 24 for the amount and account number are provided, on their right-hand ends, with slots 30 and 31 (Fig. 9) used in calculating the symbol. The slots 30 are associated with the units order of the symbol and the slots 31 with the tens order. The hundreds order receives the overflow from the slots 31 of the tens order.

The mechanism by which these slots calculate the symbol will now be described. A plurality of carriers 33, one for each rack 24 associated with the amount and account number banks, are connected to a corresponding number of arms 34 loosely mounted on shaft 35. A roller 32 is attached to the side of each carrier 33 and extends into its respective slot 30. Each carrier 33 is formed of two similarly shaped plates, having pivoted therebetween an actuating wheel such as 38, which is permanently in mesh with intermediate wheels 36 and 37. By shifting the rack 24 longitudinally, the carrier 33 is lifted or lowered by the cam slot 30 and roller 32. When this takes place, the wheel 38 rolls on the wheel 36 rigid on a fixed shaft 43 and transmits the actuating motion, in the manner of a planet gear, to the double pinion 37, 39 loose on shaft 44. This actuation is transmitted from the gear 39 through the gear 40, associated with the next rack 24, to the double pinion 41, 42 loosely mounted on the shaft 43, the actuation thus being transmitted from gear 42 to gear 45 for the next rack, and so on from gear to gear until the gear 46 secured to shaft 44 has received the movement. Since every carrier raised or lowered contributes an additional movement through its actuating wheel, the gear 46 receives the sum of all the motions imparted to the actuating wheels, and since this gear is fast to shaft 44, the movement is transmitted to a disc 48, splined to the shaft, and to a transmission gear 50 rigid thereon. The described actuating mechanism calculates only the units place of the symbol. The mechanism for calculating the tens place is supported on shafts 51 and 52. The cam slots 31 of the racks 24 act upon rollers 53 on carriers 54 to move the actuating wheels 59 of the tens order up or down. The carriers 54 are connected to arms 56 and operate in a manner similar to the carriers 33. The actuating motions of the individual racks are transmitted additively to the last gear 62, from the gear 58 fixed to the rigid shaft 51, through the gears 59 and double gears 60, 61, in the same manner as described for the units order, the gear 62 also receiving the overflow from the units order. The gear 62 is fixed to the shaft 52, and thereby controls the rotation of the gears 71 and 75.

and 82 fixed thereto, and the setting of the disc 70 splined thereon.

If in the units order several racks have been shifted to such an extent that the total of the actuations exceeds 9, then the required tens transfer is effected by a cross wheel 73 (Fig. 7-B) secured to the shaft 44, together with gear 46. A roller 74 on the cross wheel engages the slots in a mutilated Maltese cross 76 to actuate it to effect the tens transfer. The Maltese cross has rigid to it a cam disc 77 which by means of rollers 79 rocks a rocking arm 78 mounted on shaft 52 in such a manner that an actuating wheel 81 pivoted at 80 on arm 78 executes an actuating motion in the same manner as the actuating wheels 59. Since there is never more than two units to be transferred to the tens order, the Maltese cross 76 having the two slots 75 is sufficient to receive the successive actuations of cross 73.

A transfer to the hundreds place is effected in a conventional way by a mutilated gear 82 and a wide pinion 83 (Figs. 7-B and 11-B). The latter is actuated by the gear 82 and rotates the hundreds gear 84 rigid to shaft 69, which in turn sets the disc 85 splined thereon. The symbol corresponding to a particular setting of the racks thus has been calculated and transmitted to the discs 48, 70, and 85.

It is obvious that when the racks 24 are shifted from one setting to another during successive machine operations, the carriers 33 will rotate the pinions 37-40, etc., and the transfer mechanism either forward or backward directly to the new setting without first returning it to a home position. From Fig. 7-B it is apparent that a reverse rotation of cross wheel 73 will restore a previous transfer movement given the disc 77 and rocking arm 78.

The gear 58 secured to the units shaft 44 is connected to a gear 68' through the gears 63, 64, 65, 67, and 68, so as to impart to the gear 68' whatever setting is given the shaft 44 and disc 48. Likewise the gear 71 secured to the tens shaft 52 is connected to a gear 72' through the gear 72, while the gear 84 secured to the hundreds shaft 69 meshes directly with a gear 84'. These three gears 68', 72', and 84' are connected, by any suitable mechanism, to pinions 25' (Figs. 7-B and 12) to set the calculated symbol on the printing wheels 20. One such form of connection is shown by the racks 24 (Figs. 7-B and 10-B) meshing with both the wheels 68', 72', and 84' and the wheels 25', which are in turn connected to the printing type wheels 20 (Fig. 12) by sleeves 26'.

The differential movement of the racks 47, as controlled by the symbol set up on the keyboard, is transmitted, as before mentioned, to the three gears 86, 88, and 90 (Fig. 11-B). Gear 86 is journaled on the units shaft 44 and carries a pin 87 on one side thereof, while gears 88 and 90 are journaled on the tens and hundreds shafts 52 and 69, and carry pins 89 and 91.

The discs 48, 70, and 85 are normally disconnected from the gears 86, 88, and 90, so that they may be set independently. The pins 87, 89, and 91 are so positioned on the gears that when the symbol set up on the keyboard corresponds with that calculated by the set-up transaction, they will lie opposite one of the notches 92 (Figs. 8 and 11-B) in each of the discs.

The mechanism for controlling the use of the symbol computing mechanism is illustrated in Figs. 5-A, 5-B, 6, 7-A, 7-B, 11-A, and 11-B,

and has a driving shaft 93, the motion of which is transmitted through bevel gears 94, 95 (Figs. 5-B and 11-A) to a shaft 96. Cam discs 97 and 98 (Figs. 5-A and 11-A) are secured thereon and co-operate with rollers 100 and 99 mounted on draw bars 101 and 102. The draw bar 101, pivoted on links 106 and 109, mounted on shafts 107 and 108, respectively, has the roller 100 thereon held in contact with the cam disc 97 by a traction spring 105, so that the bar moves to the left after the cam disc 97 has rotated approximately 180 degrees counter-clockwise. The link 106 is secured to shaft 107, which has also secured to it a lever 110 which raises a blocking rod 111 guided in a plate 112. Whether or not the draw bar 101 may move to the left depends upon the position of a recess 123 provided on rack 113, situated above the rod 111 and having its movement governed by the differential mechanism situated under the keys 15. The connections from the keys 15 to the rack 113 includes the mutilated segment 400 (Fig. 6) adjusted to a position under the inner end of a depressed key by the differential mechanism. This segment meshes with gear 401 which transmits its movement through the gears 402, 403, 404, 405, and 406 to the rack 113. The recess 123 in rack 113 is so formed and positioned that it allows the draw bar 101 to move to the left only when the keys 15 assigned to the positive and negative old balances are depressed. This control is provided so that the mechanism now being described will operate only if and when an old balance is picked up.

Another draw bar 103 lies parallel to the bar 101 and is likewise urged toward the left by a spring 104. This bar is suspended from a bell-crank lever 132 secured to shaft 131, and a lever 124, on shaft 218. This draw bar 103 is held against movement to the left by a stud 125 on the lever 124 resting on an arm 126 pivoted at 259 to the bar 101. This arm 126 is urged clockwise by a spring 127 and is restrained by a stop stud 128.

When the machine is operated to pick up an old balance, the draw bar 101 moves to the left, carrying with it the arm 126. This allows the lever 124 to rotate clockwise and the bar 103 to move to the left under the influence of spring 104. At the end of the operation the cam 97 returns the bar 101 to the right, but since the stud 125 is now lying at the side of arm 126, the arm moves counter-clockwise about its pivot, tensioning spring 127. The bar 103, of course, remains in its left-hand, or operated, position.

Draw bar 103 is connected to the printing wheels through the lever 132 (Fig. 7-B) and the link 134 (see also Fig. 12), and is connected to the keyboard by parts shown in Figs. 5-B, 6, and 11-B. These figures show a detent 202 mounted in a conventional manner on arms 311 and 312 and having lugs 212 in position to co-operate with studs 203 projecting from the keys in row 15. It will be noticed that in the normal position of the parts, as shown in Fig. 6, the lugs 212 under the POB and NOB keys are out of line with the studs 203, so that an old balance may be entered. The lugs 212 under the other keys are, however, directly under their studs 203, so that deposits or withdrawals may not be made with the detent in this position.

This detent is connected to the bar 103 (Fig. 6) by a train of connections including a link 216 (Figs. 5-B and 6) flexibly connected to a link 214 by a spring 215, bell crank 213-a, link 213-b 75

(Fig. 5—B), arm 133 secured to shaft 131, and bell crank 132.

When an old balance is entered the spring 104 moves the bar 103 to the left when the machine has completed about one-half the operation. This movement lowers link 214 and tensions a weak spring 215, the link 216 and detent 202 being held in their upper positions by the stud 203 on the depressed old balance key lying under its lug 212. Now, when the keys are released near the end of the operation, as is customary in the art, the tension of spring 215 pulls link 216 and detent 202 downward sufficiently to lock out the old balance keys and to unlock the deposit and withdrawal keys D and W for the next operation.

The deposits or withdrawals may now be entered, during which operations the shaft 96 executes, in effect, idle movements.

The next operation in the normal course of business is that of taking the new balance, which consists of moving the lever 17 (Fig. 1) into its new balance position and depressing the motor key 19. This causes the differential mechanism under the row of keys 15 to be arrested in one of two positions between the keys W and POB in this bank. The mechanism for taking the new balance and for causing such an arresting movement is not shewn herein, as it is not necessary to an understanding of the present case. It is, however, fully shown and described in the United States Patents Nos. 1,899,455 and 2,052,444 issued to Ernst Breitling. With the differential stopped in this position the slide 113 is arrested in a position where the tapered notch 122 (Figs. 5—A and 7—A) on the under side thereof rests over the pointed end of a bell crank 114. This allows the bell crank 114 to move counter-clockwise under the influence of a spring 115, lowering a link 116 as well as the left-hand end of a link 118 pivoted to a lever 117. The lever 117 is pivoted on a rod at its mid portion and is connected at its lower end to a bar 102 (Figs. 5—A and 11—A). A nose 119 on the left end of link 118 lies in the same plane as an arm 120 connected to the lever 124 by a sleeve, and is lowered into the path of arm 120 by the lowering of link 116.

Toward the end of this new balance operation the cam 98 secured to shaft 96 moves the bar 102 to the right, moving link 118 to the left and causing the arm 120 and bell crank 124 to rotate counterclockwise about shaft 218, thereby restoring the bar 103 to its right-hand or home position. This movement also causes the rod 125 to be raised and thereby allow spring 127 to restore arm 126 to the position shown in Figs. 5—A and 7—A. The return movement of the bar 103 also causes the slide 202 (Figs. 5—B and 6) to be returned to the position shown in these figures, where the old balance keys are free to be depressed for the next bookkeeping transaction.

It is apparent that the bar 101 receives no actuation during deposit and withdrawal operations or during operations for taking the new balance, since the rod 111 can move upward to allow an operation of the bar 101 only when the slide 113 is positioned for old balance operations.

We will now consider the operation of this mechanism when an improper keyboard setting is made for the entry of an old balance in the machine. When an incorrect setting is made on the keyboard and the machine is operated, the symbol computing mechanism adjusts the discs 48, 70, and 85 (Fig. 11—B) to the position corresponding to the keyboard setting of the amount and account number. Also, the differential

mechanism for the symbol keys 12 causes the gears 86, 88, and 90 to be adjusted to the position corresponding to the keyboard setting of these keys. If the amount has been correctly set up, when the cam 97 releases bar 101 for movement to the left, bell crank 109 (Fig. 5—B) is rotated clockwise, lowering arm 146. This lowers an arm 147 (Figs. 5—B and 7—B) secured to shaft 148, and moves the upper ends of yokes 149, 150, and 151 (Figs. 6, 8, and 11—B) toward the front of the machine. These yokes (Fig. 6) lie within shouldered recesses on the back of discs 48, 70, and 85, and thereby carry the discs with them. Now, since the symbol calculated by the symbol computing mechanism and set up on discs 48, 70, and 85 is not the same as that set up on the keys 12 and gears 86, 88, and 90, the notches 92 in the discs 48, 70, and 85 do not properly align with the studs 87, 89, and 91 on the gears 86, 88, and 90, and movement of the members 146, 147, and 148 (Figs. 5—B and 7—B) and the yokes 149, 150, and 151 (Figs. 6, 8, and 11—B) is prevented, in turn preventing a movement of the bar 101 under the influence of spring 105. This causes the rod 125 to be held in its upper position and thereby causes the bar 103 to be held in its right-hand or home position. Since the bar 103 is held in its right hand or home position when an improper keyboard setting is made, it follows that the detent 202 (Fig. 5—B) will remain in its home position, and therefore a "deposit" or "withdrawal" key cannot be depressed following an incorrect entry of an old balance. When the bar 103 and the parts 132 and 134 are so held during an operation, a * on the type wheel 29—a is held in position to print on the detail strip beside the calculated symbol, showing a faulty keyboard set up. Such a * is shown on the right-hand side of the detail strip shown in Fig. 4.

After an incorrect setting has been made on the keyboard and the incorrect setting has been entered into the machine, it is necessary that a new balance operation be performed to clear the incorrect data from the machine. During such operation the printer is controlled to make a record of the improper entry and the new balance operation. This is accomplished by again having the * printed on the detail strip and by crippling the type hammers that print the symbol number and balance on the customer's card or passbook. The printing mechanism, together with this crippling mechanism, will now be described.

Referring to Figs. 13 to 16, upper and lower printing hammers are pivoted on shafts 303 and 301 (Fig. 13) and lie over and under the type wheels 20. These hammers are provided with the usual rubber impression blocks 183. The upper printing hammers have a pin and slot connection 181 with levers 173, 179, pivoted on shaft 189 and connected by links 177 with trip levers 168 to 174. A series of actuating cams 302 are secured to shaft 96 operated during each operation of the machine as heretofore mentioned. The trip levers 168 to 174 and the left-hand portion of the lower hammers are provided with rollers 304 bearing against the peripheries of the cams 302 through the tension of springs 305 and 306. When the shaft 96 is rotated the rollers 304 drop from the high portions of the cams to the low portions, causing the hammers to take impressions from the type wheels.

A record strip 185 is fed from a supply roll 186 over rollers 187, 188, 189, and 190 onto a storage roll 191. A cam secured to the shaft 96 actuates the lever 174 to reciprocate an arm 192

to advance the record paper and to reciprocate an arm 197 to advance an ink ribbon suspended around the rollers 194, 195, and 196 and a spool 198. The upper hammers are used to make the 5 impressions upon the record strip, while the lower hammers are used to print upon the patron's cards or passbooks.

A slide 139 (Figs. 13, 14, and 16) is positioned between the levers 168 to 174 and the rear ends 10 163 to 167 and 175 of the lower hammers. It is 15 obvious that if the upper and lower edges of this slide were continuous it would not be possible for the hammers to be actuated. This slide, however, is provided with a number of recesses 152 to 161 (Fig. 14). A recess 162 also is provided to accommodate the slide 136 moved by the bar 103 (see also Fig. 7—A). The recesses 152 to 161 are so positioned that they allow the appropriate printing hammers to make an impression during 20 the various transactions. The movement of slide 139 to the left (Fig. 14) is controlled by a roller 142 on the slide 139 contacting a plate 143 (Figs. 11—A and 16) mounted for sliding movement in the block 145 secured to the machine frame, and 25 adjusted by a depending portion 144 of the slide 113.

When a deposit operation is performed, wherein 30 one of the transaction keys D is depressed, the slide 113 and the plate 143 receive only a small movement (as can be determined by reference to Fig. 7—A), so that the roller 142 remains on the step 307 (Fig. 16) of the slide 143. Referring 35 now to Fig. 14 it is seen that in this position the upper and lower hammers for the deposit items, as well as the hammers for the date, account 40 number, totalizer sign, and feed are free to operate.

For withdrawal operations involving a depression of the W keys the slide 113 and plate 143 receive 45 a slightly greater movement to the left, causing the roller 142 to move onto the step 308 by the tension of spring 141 (Fig. 16). In like manner this causes the appropriate hammers for withdrawal transactions to be released for operation.

When the machine is operated to secure a new balance the roller 142 lies on the lowest step 309 of slide 143, causing the hammers used for balance transactions to be released for operation, 50 and when an old balance is entered by depression of one of the old balance keys POB or NOB, the roller 142 rests on the step 310, causing the appropriate printing hammers for this operation to be released. It will be noted, however, that 55 during old balance operations the lever 171 that controls the printing of the old balance on the record strip is released, whereas the printing hammer 164 of the lower set of hammers that prints on the account card or passbook is not released. These hammers are arranged in this 60 way because there is no necessity of printing an old balance on the customer's book or card.

It will be remembered that when an old balance 65 operation is performed with the correct keyboard setting, the bar 103 (Figs. 5—A and 7—A) is moved to the left and is not returned until after the new balance has been taken and printed; that is, the slide 103 is returned to the right at the end of a new balance operation. Movement 70 of the bar 103 to the left causes a corresponding movement of the slide 136 secured to the bar 103 by pin and slot connections 135 and pulled toward the right by a spring 137. When the keyboard has been given a correct setting and the bar 103 75 is moved to the left as a result thereof, the raised

portion 138 of the slide 136 is drawn to the left of the notch 162 in the slide 139. Since this raised portion 138 will remain withdrawn until near the end of a new balance operation, the slide 139 may move to the left (Fig. 14) sufficiently far to allow the roller 142 to contact the step 309 (Fig. 16) of the plate 143, making it possible for the balance hammer 164 to operate and thereby make an impression of the new balance on the account card or passbook.

It might be noted here that during the last part of the operation the bar 103 is returned to its right-hand position, and since the slide 139 is at this time in its extreme left-hand position (Fig. 14) a portion thereof lies in the path of the raised portion 138 of slide 136, necessitating the flexible connection shown between the slide 136 and bar 103. The slide returns to its normal position during the first part of the next operation (entry of an old balance), when the rack 113 moves the plate 143 and thereby cams the slide 139 to the right (Fig. 14).

If, however, an incorrect setting was made on the keyboard for the entry of the old balance, the bar 103 will not be moved from its position shown 25 in Figs. 5—A and 7—A, so that when the subsequent new balance is taken, the raised portion 138 of the slide 136 will restrict the movement of the slide 139 sufficiently that the hammer 164 (Fig. 16) will not be freed to print the new balance 30 on the account card or passbook. It will, therefore, not be possible for the holder of this card or passbook to later present the same with an incorrect new balance.

A mechanism is also provided to make it impossible 35 to perform two old balance operations in succession. To accomplish this the following mechanism, shown in Fig. 6, is provided.

A slide 201 having tapered faces resting under the two old balance keys is pivoted on an arm 204 40 at its lower end and an arm similar to arm 311 at its upper end. A link 205 is pivoted to the arm 204 and is connected to a link 206 by a pin and slot connection, the link 206 being held in its uppermost position by a spring 207. The link 206 45 is bifurcated to straddle a shaft 209 and has a stud 208 secured thereto and co-operating with a semi-circular member 210. When one of the old balance keys is depressed, the slide 205 is moved upwardly tensioning spring 207. Upon operation 50 of the machine the member 210 rotates about shaft 209 releasing stud 208 and link 206 to the action of spring 207. The stud 208 immediately assumes the upper dot and dash line position. At the end of the operation the member 210 again 55 assumes the position shown in Fig. 6, and when the depressed old balance key is released toward the end of the operation, the slide 206 drops slightly, leaving the stud 208 in the lower dot and dash line position. If it is now attempted to execute 60 a second old balance operation, a depression of one of the old balance keys will raise slides 205 and 206 so that the stud 208 will be moved immediately to the upper dot and dash line position where it will be in the path of a member 211 65 which must be moved to the left before the machine can be released.

Operation

In the following operation we will assume that 70 a patron presents his passbook to the teller in order to make a withdrawal of \$200.00, the old balance being \$500.00.

Setting up the old balance, the teller makes a mistake and sets up \$5,000.00 instead of \$500.00, 75

but sets up the proper symbol 089 for \$500.00. He also sets up the proper account number 1234. Upon operating the machine, the slide 113 (Fig. 5—A) moves to such a position that the notch 123 lies directly over the blocking rod 11. The slides 47 (Fig. 10—B) are differentially moved under control of the symbol keys to give the studs 87, 89, and 91 (Fig. 11—B) their appropriate setting, while the racks 24, controlled by the amount and account number keys, are differentially adjusted and thereby adjust the discs 48, 70, and 85 to bring the notches 92 therein to their positions corresponding to the amount and account number set up on the keyboard.

Now, since the improper amount was set up on the keyboard, the notches 92 will not lie opposite the studs 87, 89, and 91, so that when the bar 101 (Fig. 5—A) is moved to the left, it will not move far enough to release 125 from 126 and bar 103 will be held against movement to the left, in turn holding printing wheel 20—a (Fig. 12) in a position where it will print a star on the record strip.

Referring to the top line on Fig. 4, we will find a record of such an entry. In this figure it will be noticed that the symbol calculated for the amount of \$5,000.00 together with the account number 1234 is 092 and not 089 as was set up on the keyboard for the entry of the \$500.00 amount.

After this operation, the machine cannot be released for operation to enter withdrawals or deposits, because the detent 202 locks these keys against depression, and another old balance cannot be entered, because stud 208 prevents release of the machine following an incorrect entry of an old balance. Therefore, the only operation possible is to take a new balance, but such new balance would not appear in the patron's passbook because of the fact that when the slide 103 is retained in its right-hand position (Fig. 5—A) the slide 136 is retained in the path of slide 139 (Fig. 14) so that when the stepped plate 143 (Fig. 11—A) is shifted during a new balance operation, to allow the roller 142 to rest in the bottom notch 300, this slide 136 (Fig. 14) will prevent a full movement of the slide 139 and thereby cause the balance hammer 164 and the symbol hammer 175 for the passbook to be held up.

Now when the teller sets up the proper \$500.00 old balance together with the proper account number 1234 and symbol number 089 appearing on the top line of the passbook, shown in Figure 3, the studs 87, 89, and 91 (Fig. 11—B) and the notches 92 will be adjusted so as to be in proper alignment with one another. This allows the rod 103 (Fig. 5—A) to be moved to the left, so that slide 139 is moved out of the path of slide 136 and the type wheel 20—a is moved to such a position that the star will not be printed on the record strip. Such an entry is shown on the third line of Fig. 4.

The teller then enters the withdrawal item of \$200.00 shown on the fourth line of Fig. 4. During this operation the proper entry is made on the second line of the passbook shown in Fig. 3, with the slide 139 (Fig. 14) being adjusted to such a position that the notches therein will free the proper type hammers.

Now, when the new balance is taken, slide 139 is moved to its extreme left-hand position (Fig. 14) allowing the balance and symbol hammers for the passbook to print the appropriate entries as is also shown on the second line of Fig. 3. During this new balance operation, adjustment of

the slides 24 will calculate and print the symbol for the new balance, which is shown as 071 in Figs. 3 and 4.

Now, when the patron again presents his book for the entry of a transaction, the appropriate data for the entry of such subsequent transaction appears in the form of \$300.00 in the balance column and the symbol 071 in the symbol column.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims 15 which follows.

What is claimed is:

1. In an accounting machine, the combination of a series of denominational members simultaneously settable in accordance with the digits of a number, computing mechanism, symbol members set by the computing mechanism, and means connecting said denominational members with said computing mechanism whereby a symbol of said number is computed and set up on said symbol members upon operation of said denominational members.

2. In an accounting machine adapted to perform total taking operations, the combination of a totalizer for accumulating a total as the result of a computation of multi-digit numbers, means settable under control of said totalizer to positions corresponding to the digits of the total, and means operated by the settable means as they are set, for computing and setting up a symbol of said total in a total taking operation.

3. In an accounting machine, the combination of a series of denominational members simultaneously settable to represent a series of digits, a mechanism including a plurality of interconnected gears for computing a multi-digit symbol for a series of digits set on the denominational members, and means for connecting the gears for operation by the members whereby the digits of the symbol are all computed during the simultaneous operation of the members.

4. In an accounting machine, the combination of means for computing a symbol of a number entered in the machine, means operated by the computing means for setting up the computed symbol, key-controlled means for setting up a precomputed symbol of said number, means for comparing the setting of the means set by the computing means and the means set under key control for determining whether said computed symbol corresponds to said previously computed symbol, and control means for rendering the determining means ineffective during certain operations of the machine.

5. In an accounting machine, the combination of machine control means, means simultaneously settable to indicate a series of digits, means, operated by said settable means as it is being set, for computing a symbol for said series of digits, symbol members operated by the symbol computing mechanism to set up the symbol, feeling mechanism cooperating with the set symbol members and means operated by the feeling mechanism to control the machine control means.

6. In an accounting machine, the combination of a totalizer, means including a plurality of members set to different positions under control of said totalizer for setting up values standing thereon, means operable by said members as they are set to their differential positions for auto- 75

matically computing a symbol of the value being set up, and means operated by the computing means to set up the computed symbol.

5 7. In an accounting machine, the combination of a series of denominational members, said members being shiftable in either of two directions, actuating cams on said members, and symbol computing mechanism operated predetermined extents by the actuating cams on the denominational members during their movements in either direction.

10 8. In an accounting machine, means for computing a symbol for a series of digits, including members settable to positions corresponding to the computed symbol, elements directly settable to positions corresponding to a precomputed symbol for said series of digits, feeling mechanism cooperating with the set members and elements for comparing the symbol, as computed, with the precomputed symbol and means to render the feeling means operable in certain operations of the machine.

15 9. In an accounting machine, means for computing a symbol for a series of digits and for setting up said symbol, means for setting up a precomputed symbol for said series of digits, means for comparing the computed symbol with the precomputed symbol while the two symbols remain set up, an indicating means normally operable to indicate a nonagreement of the symbols, said comparing means being operable to render the indicating means inoperative when the symbols agree, and differentially operable means to render the comparing means operative only in certain machine operations and after the symbols have been set.

20 10. In an accounting machine, the combination of a totalizer, means positioned under control thereof for setting up values standing thereon, means operable by said setting up means as the setting up means is controlled by said totalizer for automatically obtaining a symbol of the value being set up, and means operated by the obtaining means to set up the obtained symbol.

25 11. In an accounting machine, a plurality of control keys for controlling the operation of the machine, means for obtaining a symbol for a series of digits, including members settable to positions corresponding to the obtained symbol, elements directly settable to positions corresponding to a preobtained symbol for said series of digits, feeling mechanism cooperating with the set members and elements for comparing the symbol, as obtained, with the preobtained symbol, and means operated under control of the feeling mechanism for selecting the control keys for operation to variously control the operation of the machine in accordance with whether the symbols are the same or different.

30 12. In an accounting machine, key-controlled means for obtaining a symbol for a series of digits and for setting up said symbol, key-controlled means for setting up a preobtained symbol for said series of digits, mechanical means for comparing the obtained symbol with the preobtained symbol, an indicating means normally operable to indicate a non-agreement of the symbols, said comparing means being operable to render the indicating means inoperative when the symbols agree, and control means for allowing the operation of the comparing means in only certain machine operations.

35 13. In a machine of the class described, the combination of a plurality of type carriers; differentially positionable means for setting the type

carriers to indicate amounts; means, operated by the differentially positionable means as they are operated to set the type carriers, for computing a short symbol of the amount simultaneously with the setting of the amount on the type carriers; type carriers set by the symbol computing means; and means cooperating with the type carriers to simultaneously print the amount and its related short symbol.

40 14. In an accounting machine adapted to perform total taking operations, the combination of a totalizer; differential members settable under control of the totalizer to positions commensurate with the digits of the total on the totalizer; symbol computing mechanism; and means on the settable members operable to impart predetermined increments of movement to the symbol computing mechanism when the members are set under totalizer control.

45 15. In a machine of the class described, the combination of key-controlled differential mechanism; a plurality of type carriers; a plurality of members simultaneously positionable by the differential mechanism and operable to set the type carriers to represent a series of digits; means operated predetermined extents by the members as they are operated to set the type carriers, for obtaining a short symbol for said series of digits; type carriers operated by said obtaining means to set up the symbol simultaneously with the setting of the type carriers for said series of digits; and means cooperating with the type carriers for said series of digits and said symbol type carriers for printing said series of digits and said symbol simultaneously.

50 16. In a machine of the class described, the combination of a plurality of denominational members settable to represent a series of digits; symbol computing mechanism including a plurality of trains of gears, each train of gears comprising a plurality of gears mounted on fixed supports and a plurality of gears mounted for movement relative to the fixed supports; means on the members operable to shift the gears, which are mounted for movement, to cause the trains of gears to receive predetermined increments of actuation as the denominational members are set, to thereby compute a symbol related to the series of digits; and means operated by the symbol computing mechanism for setting up the computed symbol.

55 17. In a machine of the class described, the combination of a plurality of members simultaneously settable to represent a series of digits; symbol computing means including a plurality of trains of gears; means on the members operable to give certain of said gears predetermined increments of movement when the members are set to represent the series of digits to thereby compute a symbol for that series of digits; and means settable by the computing means to set up the computed symbol.

60 18. In a machine of the class described, the combination of a plurality of denominational members simultaneously settable to represent a series of digits; symbol computing means including a plurality of trains of gears, each train of gears comprising a plurality of gears mounted on a fixed support and a plurality of gears mounted on movable supports; a plurality of actuating means on each of the members for shifting the movable supports for the gears in the plurality of trains of gears predetermined extents when the members are set to represent said series of digits.

- to thereby actuate the symbol computing means; and means operated by the symbol computing means for setting up the computed symbol.
19. In a machine of the class described, the combination of a plurality of denominational members; means to set said members to represent digits of numbers; mechanism for computing an identifying symbol for each of said numbers, including symbol wheels and a series of interconnected gears for operating each symbol wheel; and means on each of the members for operating the gears of the series in accordance with a predetermined rule whereby the setting of each symbol wheel will be controlled by all the members.
20. In a machine of the class described, the combination of a plurality of denominational members; means for simultaneously and differentially operating said members to set up a series of digits; mechanism for computing a multi-digit symbol representing the series of digits set on the denominational members; and operating connections between each of said members and the computing mechanism for operating the computing mechanism by the members according to a predetermined rule for various digit values as they are set up on said members, said operating connections enabling every denominational member to exercise a control over the computation of each digit of the symbol.
21. In an accounting machine, the combination of means for computing a symbol of a number entered in the machine; key-controlled means for setting up a previously computed symbol of the number; mechanical comparing means, acting while the symbol remains set, for determining whether the computed symbol corresponds to the previously computed symbol; and means for rendering the comparing means effective during certain operations of the machine.
22. In an accounting machine, a plurality of control keys; a keyboard for controlling the entry of amounts; means for computing identifying symbols for the amounts entered; a separate symbol keyboard for controlling the entry of previously computed identifying symbols related to said amounts; means set under control of said symbol keys to indicate the precomputed symbols; means for comparing the symbol set up under control of the symbol keys with the symbol computed by the symbol computing mechanism; and means controlled by the comparing means and selectively cooperable with the control keys to select certain of said control keys for operation if the symbols agree and to select other ones of the control keys for operation if the symbols do not agree.
23. In an accounting machine adapted to perform old balance entering operations and other types of entering operations, a totalizer; means for entering an old balance thereon during a machine operation; means operable during said old balance entering machine operation for computing a symbol representing the old balance; means operable during said old balance entering machine operation to set up a precomputed symbol related to the old balance; means for de-
- termining whether the computed symbol agrees with the precomputed symbol; and means for preventing another old balance entering operation on the next succeeding machine operation if the symbols agree.
24. In an accounting machine, a totalizer; means for entering amounts therein during old balance and item entering machine operations; old balance entry control devices; item entry control devices; means for computing an identifying symbol representing an old balance during said old balance entering machine operation; means for setting up a precomputed symbol related to said old balance; means for determining whether the symbols agree; and means for locking the item entry control devices against operation until the proper old balance has been entered into the totalizer as determined by the agreement of the symbols.
25. In an accounting machine, a plurality of members simultaneously movable to positions to represent a series of digits; means to move the members from the positions representing one series of digits directly to other positions representing another series of digits without returning the members to zero position; reversibly operable means for computing an identifying symbol representing a series of digits set up on the members; and means operated by said members to actuate the computing means predetermined extents in either of two directions as the members are set directly from one digit value to another so that a new symbol is computed directly without first clearing out a previously computed symbol.
26. In an accounting machine, the combination of a plurality of simultaneously operable denominational members, said members being shiftable in either of two directions to positions representing digits; symbol obtaining mechanism for obtaining a symbol representing the digits which are set on the members; and actuating means on said denominational members for giving the obtaining means variable preselected increments of actuation during the movement of the members in either direction to positions representing digits.
27. In a machine of the class described having a plurality of sets of type carriers, and impression means simultaneously cooperable with the sets of type carriers to record the data set up thereon, the combination of a plurality of differentially positionable means for setting the type carriers of one of said sets to indicate an amount; means operated predetermined arbitrary extents by the differentially positionable means, as they are operated to set said one set of type carriers to represent an amount, for computing a symbol representing said amount; and means operated by the symbol computing means for setting another of said sets of type carriers to set up said symbol along with the setting of the amount on the first set of type carriers so that an impression of the amount and its related symbol can be made simultaneously.

KURT AURBACH. 65
